UNITED STATES PATENT OFFICE

JAMES A. ANDERSON, OF MINNEAPOLIS, MINNESOTA

DESIGN FOR A BOOK END

Application filed May 24, 1930. Serial No. 35,763. Term of patent 3½ years.

To all whom it may concern:

Be it known that I, JAMES A. ANDERSON, a citizen of the United States, residing at Minneapolis, in the county of Hennepin and State of Minnesota, have invented a new, original, and ornamental Design for Book Ends, of which the following is a specification, reference being had to the accompanying drawings, forming part thereof.

Fig. 1 is an elevational view and Fig. 2 is a perspective view of a book end, showing my new design.

I claim:

The ornamental design for a book end, as shown.

JAMES A. ANDERSON.
